CABLE CAR DRIVE-IN RESTAURANT

Wesley A. MacDuckston, 1 Sola Ave.,
San Francisco, Calif.

Filed Oct. 1, 1964, Ser. No. 81,962

Term of patent 14 years

(Cl. D13—1)

FIG. 1

FIG. 2

FIG. 3

FIG. 4

FIG. 5

FIG. 1 is a top plan view of a cable car drive-in restaurant of my new design;

FIG. 2 is an elevational view showing one side of my new design;

FIG. 3 is an elevational view of the side opposite that shown in FIG. 2;

FIG. 4 is a rear elevational view of my new design, and

FIG. 5 is a front elevational view of my new design. I claim:

The ornamental design for a cable car drive-in restaurant, as shown and described.
